Primary Examiner — Sheryl Lane(74) *Attorney, Agent, or Firm* — Robert C. Montgomery; Montgomery Patent & Design, LP**CLAIM**

The ornamental design for a rake with a wrist attachment, as shown and described.

DESCRIPTION

FIG. 1 is a perspective front view of the rake with a wrist attachment, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is bottom view thereof.

The broken lines represent portions of the rake and form no part of the claimed design.
